UNITED STATES PATENT OFFICE.

WILLIAM W. ST. JOHN, OF ST. LOUIS, MISSOURI.

PISTON-PACKING.

SPECIFICATION forming part of Letters Patent No. 245,236, dated August 2, 1881.

Application filed March 30, 1881. (No model.)

To all whom it may concern:

Be it known that I, WILLIAM W. ST. JOHN, a citizen of the United States, residing at St. Louis, in the county of St. Louis and State of Missouri, have invented new and useful Improvements in Piston-Packings, of which the following is a specification.

This invention relates to that class of piston-packings in which a seat-ring or bull-ring carries one or more expansible packing-rings. Its objects are to prevent the packing-rings from moving laterally in their seats, to insure the prompt response of the packing-rings to steam-pressure, to facilitate the wearing of the packing-rings to form snug joints with the cylinder-face, to prevent the passage of steam between the cleft ends of the packing-rings, and to steady the packing in its reciprocatory movement and secure an even wear of the rings.

To these ends it consists in a novel construction and combination of the several parts of the packing, as will be hereinafter fully described with reference to the accompanying drawings, in which—

Figure 1 is a perspective view of a piston-packing constructed according to my invention. Fig. 2 is a diametric section of the same in a plane indicated by line *x x*, Fig. 1. Fig. 3 is a similar section, illustrating a modification of the expansible packing-ring. Fig. 4 illustrates a packing provided with an expansible steady-ring in addition to its packing-rings. Fig. 5 shows a modification of the same. Fig. 6. is an edge view of Fig. 5. Fig. 7 is a cross-section of Fig. 5 on line *y y*.

Referring to Figs. 1 and 2, the letter *A* denotes the cast ring, and *C C* the expansible metallic packing-rings. The packing-rings are each cut transversely at one point, are a little more than half as thick as the seat-ring, and are fitted upon annular seats formed by reducing the thickness of the seat-ring at its margins, so as to form radial walls *d d* and annular faces *e* concentric with the seat-ring. At the foot of the radial wall *d* of each seat a peripheral groove, *f*, is formed in each of the faces *e*, and into this groove fits an annular rib, *g*, projecting inwardly from the inner margin of the packing-ring. As the packing-ring expands from the faces *e* under the influence of

steam-pressure, the rib *g* still remains partially in the groove, and the ring is thus prevented from being thrown from its seat or moving laterally.

It will be observed that the construction of the annular seat *e* and of the packing-ring *C* is such that the margin of the inner surface of the packing-ring is seated directly on and supported by the annular seat *e*, which is of great advantage, because the weight of the piston is not sustained solely by the annular rib of the ring, but is uniformly supported and sustained by the annular seat *e*, and thereby the rib *g* serves solely to retain the packing-ring on its seat, whereby I am enabled to avoid the use of the usual follower-rings, resting against the outer faces of the packing-rings and bolted into place.

Laterally inward from the annular rib *g* projects a light annular flange, *h*, and laterally outward from the outer edge of the radial wall *d* projects a similar flange, *h'*. The former sets against the radial wall *d*, and the latter impinges against the adjacent face of the packing-ring. The chamber formed between these two flanges collects the surplus oil, which would otherwise be forced into the various joints and impair their snugness of fit. By reducing the surfaces in contact I also reduce the friction between the radial wall and the ring, and the latter responds more readily to expanding steam-pressure. The rib *g* also serves the purpose of holding the main portion of the inner periphery of the ring *C* at a little distance from the face *e* of its seat, and thus provides ready access for steam under the ring, so that it will promptly respond to even a light steam-pressure.

In the modification shown in Fig. 3 the inner radial face of the packing-ring *C'* is fitted snugly to the plain radial wall of the seat, the flanges *h* and *h'* being omitted. Very good results are got from this construction; but I prefer to use the flanges, especially in packings of large size.

At a given point in each outer margin of the seat-ring is fitted a metallic cylindrical button, *I*, which sits flush and loosely in a corresponding seat, which seat extends partly into the intermediate part of the seat-ring between

the packing-ring seats and partly across the annular circumferential face *e* of the ring-seat. That portion of the button which projects laterally beyond the radial wall has its outer portion cut away to form surfaces coinciding with the surfaces of said wall and the annular face *e*, except that the vertical face of the button has no flange, as at *h'*, and is simply grooved at its base to receive the flange *h* of the packing-ring, the walls of the ring and button coming snugly together outwardly from said flange. The cut-away part of the button, in fact, forms a small section of the packing-ring seat, and it is in it that the two ends of the packing-ring meet or nearly meet, as shown in Fig. 1. The button being loose in its seat, and the flange *h* taking into the groove in said button, the latter will be moved outward as the ring expands and bridges the space between the ends of the ring, so that no steam will pass through said space. The ring is thus rendered practically steam-tight all around, while at the same time its expansion is not in the least restricted.

25 I prefer to provide the button *I* with a stem, *I'*, which projects inwardly through an aperture in the seat-ring and has its tip resting upon a spring, *k*, the other end of which supports the stem of the button at the other side of the ring. This spring is supported by the head of a screw, *l*, tapped into the seat-ring, and which should be screwed up tight enough to force the buttons outward, in order that the expansion of the packing-rings may run no risk of being retarded by the sticking of the buttons. In fact, in the modification shown in Fig. 3 the entire labor of forcing out the buttons is devolved upon the springs, as the rings and button are not engaged.

40 I prefer that the two buttons of each packing-ring shall not be directly opposite each other, as the cutting of both button-seats on one transverse line would possibly weaken the the seat-ring, and, besides, creates too great an interruption of the intermediate face of said ring, which, indeed, is sometimes not wide enough to permit the buttons to be arranged opposite each other. The spring *k* is arranged obliquely, in order to bear upon both the button stems.

45 In order that the packing-rings may not move circumferentially in their seats, a locking-pin, *m*, for each is inserted in the seat-ring in such position that a part of the body of the pin lies in a groove in the radial wall of the ring-seat and part within a groove in the adjacent face of the packing-ring.

50 Each of the packing-rings *C* has in its outer face a wide peripheral groove, leaving projecting two narrow annular beads, *c e*. The object in forming the ring with these narrow beads is to facilitate its wearing away to conform to the inner surface of a cylinder at the commencement of using the packing. I find that with these beads the packing very quickly takes the steam in an efficient manner, and gradually wears to a full seat more quickly

than when the full face is at first presented to the cylinder.

In order to secure an even wear on both packing-rings, avoid thumping, and provide for a steady movement of the packing, I provide the seat-ring with an expansible steady-ring, as shown at *N* and *N'* in Figs. 4, 5, 6, and 7. For this purpose, as shown in Figs. 4 and 7, a wide peripheral groove is formed in the intermediate face of the seat-ring, leaving stationary only narrow faces *n n*, as in Fig. 4, and *n' n'*, as in Fig. 5. A stationary abutment, *O*, is, however, shown as inserted in the groove in Fig. 8, to receive the buttons *I I*. The ends of the expansible packing-ring *N* come close to the opposite ends of this abutment.

Screws *p p p p* are tapped in the seat-ring from the interior, and their tips impinge against the inner surface of the steady-ring, as shown in dotted lines, Fig. 6. By setting outward these screws the steady-ring is expanded to compensate for wear and to give it a firm bearing against the cylinder-face.

In Figs. 5 and 7 the abutment *O* is dispensed with, the portions *n' n'* of the intermediate face of the seat-ring being wide enough to receive the buttons. In this modification the ends of the steady-ring *N'* come close together.

Heretofore piston-packings have been known in which expansible packing-rings are supported away from the radial walls formed on the bull-ring by intermediate flanges to create intervening spaces; but in such packings, as heretofore known, it has been necessary to employ followers to confine the packing-rings on the bull-ring. Piston-packings have also been provided in which the expansible packing-rings have been provided with an annular flange arranged in an annular groove in the bull-ring; but such, broadly, I do not claim.

What I claim is—

1. A piston-packing consisting of a seat-ring, *A*, having an annular face, *e*, and radial wall *d*, provided respectively with a peripheral groove, *g*, and a lateral flange, *h'*, as described, combined with an expansible packing-ring having an annular rib, *f*, and an annular flange, *h*, substantially as and for the purpose described.

2. The combination, with the seat-ring and the cleft expansible packing-ring, of the outwardly-movable bridge-button, forming a seat for the ends of said rings, substantially as and for the purpose set forth.

3. The combination, with seat-ring and expansible metallic packing-rings, of an expansible bearing or steady-ring arranged between the expansible packing-rings, substantially as described.

In testimony whereof I have hereunto set my hand in the presence of two subscribing witnesses.

WM. W. ST. JOHN.
